UNITED STATES PATENT OFFICE.

ALBERT F. JONES, OF SALEM, MASSACHUSETTS.

COUNTER-FORMING MACHINE.

1,118,554.

Specification of Letters Patent. Patented Nov. 24, 1914.

Application filed December 22, 1911. Serial No. 667,283.

To all whom it may concern:

Be it known that I, ALBERT F. JONES, a subject of Great Britain, residing at Salem, in the county of Essex and State of Massachusetts, have invented an Improvement in Counter-Forming Machines, of which the following is a specification.

This invention relates to counter-forming machines, and is intended as an improvement upon the machine of my application for Letters Patent #498,411, filed May 26, 1909, and more particularly of my application #623,948, filed April 28, 1911. In the machine of both applications a feeding-and-bending device is employed to bend a counter-blank into heel-form, and feed it to a mold, and means are provided for moving said device toward and from the mold. It sometimes happens that the blank is twisted, or otherwise deformed, so that it will not be correctly engaged by the jaws of the feeding-and-bending device, or it is moved while held by said jaws, or a counter has not been properly removed from the mold after being molded, and in either case it will not be correctly delivered or fed to the mold, and in case said device is moved positively as it will be by actuating-means heretofore devised by me, the blank will obstruct its movement and result in the destruction of the blank and the liability of breaking the machine.

One of the objects of my present invention is to improve the means for moving the feeding-and-bending device toward and from the mold, said improved means being of a yielding character, so that, in case movement of said device toward the mold is obstructed by a deformed or incorrectly disposed blank, there will be no liability of breaking the machine.

Another object of my present invention is to provide automatic means to stop the machine in case the feeding-and-bending device should not make its complete stroke in a direction toward the mold, which it would not do if obstructed.

In the machine of my said application #623,948, the mold is arranged in vertical position and the counter-blank moved toward it in a horizontal direction, and it is difficult to accurately adjust the feeding-and-bending device with respect to the mold so that the blank will be delivered with its heel end close to the heel end of the former on which the blank is molded; and another object of this invention is to give to the

feeding-and-bending device an additional movement in a vertical direction toward the former when it has reached the end of its stroke in a direction toward the mold, thus to bring the blank into engaging position with the heel end of the former before the compressing-mechanism is operated. In the machine of the aforesaid application, the means to operate the side blank-engaging nippers or jaws is arranged partly on the main portion of the machine, and partly on the head or frame of the feeding-and-bending device, but such construction will not admit of the aforesaid vertical movement of said device, and herein the entire operating-means for said nippers or jaws is arranged on the head, thus to admit of vertical movement thereof.

Figure 1 is a front elevation of a feeding-and-bending device and means embodying my present invention for moving it toward and from the mold. Fig. 2 is a plan view of the means to move the feeding-and-bending device, the parts being in the position they will occupy when the blank is brought into the plane of the mold. Fig. 3 is a similar plan view of the feeding-and-bending device and means to move it, the parts being in the position they will occupy when receiving a blank. Fig. 4 is a detail plan view of the automatic stop-motion for the machine. Fig. 5 is a detail of the means to lift the feeding-and-bending device at the end of its stroke in a direction toward the mold. Fig. 6 is an enlarged side elevation of a portion of the head, and means to operate the side blank-engaging nippers or jaws. Fig. 7 is a plan view of the part shown in Fig. 6. Fig. 8 is a sectional detail of the cam for operating the means to operate the side blank-engaging nippers or jaws. Fig. 9 is a vertical sectional detail of one of the side blank-engaging nippers or jaws arranged on the head.

The feeding-and-bending device here shown is substantially the same as shown in my aforesaid application #623,948, and is designed to take a counter-blank from a blank-adjuster and bend it into heel-form and deliver it to a mold, and comprises essentially a head 215, which is made as a yoke, and arranged at the top of a vertical spindle 216, having its bearing at the end of a longitudinally adjustable arm 217, mounted on an upright post or bar 152 to swing in a horizontal plane, the extent of oscillation being sufficient to move the head

far enough to receive the blank from one group of mechanism and to convey it to the mold. Said arm 217 is here made as a bracket, see Fig. 1, to afford a long bearing 5 on the post 152, and it has secured to its lower end a short arm 218, with or without a roll thereon, which engages a cam 222, secured to the rotating shaft 155, said cam acting to move the bracket 217 in a direction 10 to move the head 215 away from the mold, and to permit movement thereof in the opposite direction, and also to control such return movement. A spring 219 is arranged on a post on the bracket 217, the 15 lower end of which engages the bracket or an arm thereon, and the upper end of which is connected to an arm extended from a sleeve 220, having its bearing in a boss on the side of the upper portion of 20 the bracket, and said sleeve has secured to its upper end a horizontally arranged quadrant 221, to which one end of a cord 223 is attached, the other end of said cord being attached to a stationary post, which may be 25 a part of the frame of the machine. As the bracket is swung outward, in a direction away from the mold, by the cam 222, and the quadrant and spring thereby moved bodily with it a pulling force upon the cord 30 results, which acts to turn the quadrant and thereby to wind the spring, and as soon as said cam 222 permits of return movement of the bracket, such return movement will be caused by the spring unwinding, but will 35 be controlled by the arm 218, or roll thereon, continuously engaging said cam 222. Thus movement of the bracket and head carried by it in a direction toward the mold is 40 spring actuated, yet is controlled by the cam, and in case such movement is obstructed it will cause no greater pressure upon the obstruction than the force exerted by the spring, and liability of breaking the machine is avoided.

45 Each time the bracket 217 completes its stroke in a direction toward the mold it operates means to disconnect the elements of a stop-motion mechanism, so that the stop-motion will not be operated to stop the machine, but in case the bracket does not complete its stroke when moved in a direction 50 toward the mold, as for instance, if said movement should be obstructed, then said stop-motion mechanism will not be disconnected, and will be operated to automatically 55 stop the machine.

Referring particularly to Fig. 4, 500 represents a cam secured to the rotating shaft 155, which is designed to make one revolution during each complete operation of the machine, and 501 is a lever engaging said cam having its hub 502, mounted loosely on the upright post 152, and 503 is a lever extended from said hub bearing a pin 504. A 60 spring 505 is connected at one end to said le-

ver 503, and at the other end to a fixed post, which acts to hold the lever 501 in continuous engagement with the cam 500. A bar 506 is pivotally connected at one end to a short arm 507, which is connected to a pivot-shaft 508, to which a clutch-lever 509 is secured, which is connected with a clutch-mechanism of any suitable construction, and movement of said lever 509 in the direction of the arrow, Fig. 4, acts to operate the clutch to stop the machine, while movement in the opposite direction acts to operate the clutch to start the machine. For the purpose of operating said clutch lever 509 by hand, a hand-lever 510 is here shown as connected to said pivot-shaft 508, by which to turn it. The bar 506 extends in a direction toward and terminates near the extremity of the lever 503, and its end is formed with a shoulder 512, which is adapted to be engaged by the pin 504 on the lever 503, so that when said lever is moved by the cam said bar will be moved longitudinally, and the short arm 507 moved to turn the pivot-shaft and thereby move the clutch-lever 509 in the direction 75 of the arrow. Said bar 506, however, is movable on its pivot so that its shouldered end is movable into and out of position to be engaged by the pin 504, and when moved out of position to be engaged by said pin, movement of the lever 503 will not operate to move the clutch-lever 509. The position of said bar 506 relative to the lever 503 is controlled by the bracket 217, and, as here shown, said bar 506 is slotted, as at 513, to receive a pin 514 borne by an arm 515, secured to the upper end of a shaft 517, having its bearings in ears secured to the post, and an arm 518 is secured to the lower end of said shaft 517 having a pin 519 extended downwardly from it, which is arranged to be engaged by the bracket 217 when said bracket arrives at the end of its stroke in a direction toward the mold. When the pin is struck by the bracket said arm 518 is moved and its shaft 517 turned, and the arm 515 swung in a horizontal plane thereby to move the bar 506 on its pivot, out of position to be engaged by the lever 503. As the bracket is moved in the opposite direction said shaft 100 517 and parts connected therewith are returned to normal by means of a spring 520, which is arranged upon it, and is connected at one end with it and at the other end with a fixed support. In fact, this spring acts not 105 only to hold the shaft in normal position but also the bar 506 in position to be engaged by the lever 503. In case the bracket meets with an obstruction on its way to the mold, it will be apparent that the pin 519 will not 110 be engaged, hence the bar 506 will not be moved and will remain in position to be engaged by the lever 503, so that the clutch-lever will be operated. The automatic stop-motion here shown is intended to illustrate 115 120 125 130

only one of the many forms which may be employed as coming within the scope of my invention.

Referring to Figs. 1 and 5, a lever is pivotally supported on the bracket 217 at 530, one end of which, as 531, extends beneath the lower end of the spindle 216 of the oscillating head of the feeding-and-bending device, and the other end of which, as 532, is movable into and out of position beneath one end of a cam-lever 533, as the bracket is oscillated, said end portion 532 coming beneath said cam-lever when the head has arrived at the end of its stroke in the direction toward the mold, so as to be operated by said cam-lever at this time to lift the spindle 216 axially to raise the head, and thereby to move the blank which is held by the jaws into engaging position with the heel end of a vertically disposed mold-former 426. The cam-lever 533 is arranged to be operated by a cam 534, secured to the rotating shaft 155, once during each operation of the machine and is timed to operate the cam-lever at the moment the head has carried the blank into the mold, or into the plane of the mold-former thereof. The cam-lever is pivoted at 535, and is counterbalanced by a weight 536. In order that the feeding-and-bending device may be raised when it has arrived at the end of its stroke in a direction toward the mold, and not release the blank held by it, it has been reconstructed in some particulars, as compared with the device of the machine of the aforesaid application, as will now be described.

In the present construction the means to oscillate the head to feed the blank from a blank-adjuster to the mold is arranged entirely above the bracket 217, and referring to Figs. 1 to 3, an arm 225 is arranged at right angles with respect to an arm 550, extended from the base of the yoke or head 215, and said arm 225 bears at its extremity a pin 226, with or without a roll thereon, which enters a groove or way formed in the upper side of an angularly formed plate 227, which is rigidly secured to an arm 551 fixed to the post 152, at a point above the bracket 217. As the bracket swings and the head is caused to travel in the arc of a circle the pin 226 will follow in the groove in the plate 227, and as a result the head will be oscillated, moving from the position shown in Fig. 2, to the position shown in Fig. 3. Said groove or way is of sufficient depth to permit the pin 226, or roll thereon, to remain in engagement with it, when the head is raised by the lever 531.

In the machine of the aforesaid applications, the head has three pairs of blank-engaging nippers, one pair to engage the middle of the blank as 230, 231, and two pairs to engage the sides thereof as 250, 251, but the present invention has to do only with

the two side blank-engaging nippers, both of which are represented in Fig. 2 and one only of which is represented in Fig. 9. These side nippers are movable on horizontal axes and also are movable bodily in the arc of a circle thereby to bend the ends of the blank upward and inward while it is held by them, and said movements are given to said side nippers during the travel of the head. The nipper-frames 254, are pivoted on horizontal pivot-studs 285, loosely connected to the extremities of a pair of oppositely extended arms 286, respectively secured to a pair of short horizontal shafts 287, having their bearings in the head, and said shafts have secured to them pinions 288, arranged a short distance apart, and both pinions are engaged by a double rack-bar 289, which is arranged vertically between them, so that downward movement of said rack-bar acts to revolve said pinions in opposite ways, and thereby to move the arms in opposite ways and lift the nipper-frames in the arc of a circle. Said nipper-frames have secured to them guiding-plates 290, which engage one or the other side of a recessed guideway 291, on the head, and, as the nipper-frames are pivotally connected with the arms 286, it will be seen that as the arms are moved and the nipper-frames lifted by them, said nipper-frames will be turned on their pivots in opposite ways, hence the nipper-frames are turned while being lifted, the combined movements acting to bend the ends of the blank upward and inward and cause it to assume a heel-form. To move the rack-bar vertically improved means are here provided which are self-contained on or in connection with the head, so that as the head is raised by the lever 531, said rack-bar will be raised with it, whereas in the construction of the machine of the aforesaid application such lifting movement of the head is with respect to the rack-bar, and in such case the pinions will be turned by the rack-bar as they are moved bodily with respect thereto by an upward movement of the head. As here shown, the rack-bar 289 is connected at its lower end by a swivel connection, with a lever 560, secured to a pivot-shaft 561, and a bell-crank lever is secured to said pivot-shaft, one arm of which, as 563, is connected by an adjustable link 564, with a lever 565, secured to the upper end of a vertical shaft 566, to the lower end of which shaft a lever 567, is secured having at its extremity a pin 568, with or without a roll thereon, which engages a cam 569, adjustably secured to the sleeve-bearing for the spindle 216, and which is thus stationarily supported. As the head is oscillated the cam-lever 567 travels about the cam 569, a part of a cycle, and is moved by said cam thereby to oscillate the shaft 566, and move the lever 565 to 130

in turn move the bell-crank lever and turn the shaft 561, and lift the lever 560 and thereby move the rack-bar to rotate the pinions. The other arm 570 of the bell-crank lever has attached to it a weight 571, which acts to assist the cam 569 in performing its functions, although said weight alone is not sufficient to move the rack-bar and rotate the pinions. When the head is moved in a direction away from the mold, into the position shown in Figs. 3 and 7, the cam-lever 567 will engage a stationary bar 580, which acts to thrust said lever in a direction toward the cam, thereby to restore the parts. Said bar 580 may be secured to the bar 551, or to some other suitable support. As the head is raised by the lever 531, the cam-lever 567 will slide vertically on the face of the cam 569, and the relative position of the parts will not be changed during such movement, so that the blank-engaging nippers will not be operated by rotary movements of the pinions during such lifting movement of the head.

25 I claim:

1. In a counter-forming machine, the combination with a mold, of a feeding-and-bending device for the blank, a spring arranged to move said device toward the mold, and means to move said device away from the mold and to wind said spring, substantially as described.

2. In a counter-forming machine, the combination with a mold, of a feeding-and-bending device for the blank, a swinging bracket bearing it, a spring arranged to move said bracket in a direction toward the mold, and a cam arranged to control such movement and also to move said bracket in the opposite direction and to wind said spring, substantially as described.

3. In a counter-forming machine, the combination with a mold, of a feeding-and-bending device for the blank, a swinging bracket bearing it, a spring borne by the bracket and connected at one end thereto, an oscillating member borne by the bracket to which the other end of said spring is attached, a cord connecting said oscillating member with a fixed part of the frame, whereby movement of the bracket in one direction acts to wind said spring, and a cam to move said bracket in a direction to wind the spring which permits and also controls movement thereof in the opposite direction, substantially as described.

4. In a counter-forming machine, the combination with a mold, of a feeding-and-bending device for the blank, means to move said device toward and from the mold involving a yielding element permitting said device to yield in case its movement toward the mold is obstructed, a stop-motion mechanism for the machine, means to operate it, and means engaged by said device when

completing its stroke in a direction toward the mold to disconnect said stop-motion mechanism whereby it is prevented from operating, substantially as described.

5. In a counter-forming machine, the combination with a mold, of a feeding-and-bending device for the blank, means to move said device toward and from the mold involving a yielding element permitting said device to yield in case its movement toward the mold is obstructed, a stop-motion mechanism having an actuator adapted to be operated during each operation of the machine, and means movable into and out of engagement with said actuator and which is controlled by said device, said means when in engagement with the actuator permitting the actuator to operate the stop-motion mechanism and when out of engagement therewith preventing it from operating the stop-motion mechanism, substantially as described.

6. In a counter-forming machine, the combination with a mold, of a feeding-and-bending device for the blank, means to move said device toward and from the mold involving a yielding element permitting said device to yield in case its movement toward the mold is obstructed, a clutch-lever, an actuator adapted to be operated during each operation of the machine, and means connected with said clutch-lever and movable into and out of engagement with said actuator and which is controlled by said device, said means when in engagement with the actuator permitting the actuator to operate the clutch-lever and when out of engagement therewith preventing it from operating the clutch-lever, substantially as described.

7. In a counter-forming machine, the combination with a mold, of a feeding-and-bending device for the blank, means to move said device toward and from the mold involving a yielding element permitting said device to yield in case its movement toward the mold is obstructed, a clutch-lever, an actuator adapted to be operated during each operation of the machine, and means connected with said clutch-lever and which is movable into and out of engagement with said actuator and having an arm adapted to be struck by said device when arriving at the end of its stroke in a direction toward the mold, to move said means out of engagement with the actuator, said means when in engagement with the actuator permitting the actuator to operate the clutch-lever and when out of engagement therewith preventing it from operating the clutch-lever, substantially as described.

8. In a counter-forming machine, the combination with a mold, of a feeding-and-bending device for the blank, means to move said device toward and from the mold involving a yielding element permitting said

device to yield in case its movement toward the mold is obstructed, a clutch-lever, an actuator adapted to be operated during each operation of the machine, and means connected with said clutch-lever and which is normally held in engagement with said actuator, said means having an arm adapted to be engaged by said device when the latter arrives at the end of its stroke in a direction 5 toward the mold to move said means out of engagement with the actuator, said means when in engagement with the actuator permitting the actuator to operate the clutch-lever and when out of engagement therewith 10 preventing it from operating the clutch-lever, substantially as described.

9. In a counter-forming machine, the combination with a vertically arranged mold having a former, of a feeding-and-bending 20 device for the blank, means to move said device toward and from the mold, and means to raise said device when the blank held by it is in the mold, thereby to move the blank into engagement with the former, substantially 25 as described.

10. In a counter-forming machine, the combination with a vertically disposed mold having a former, of an oscillating feeding-and-bending device for the blank, means to 30 move said device toward and from the mold and to oscillate it, and means to raise said device when it has arrived at the end of its stroke in a direction toward the mold to move the blank carried by it into engagement 35 with the former, substantially as described.

11. In a counter-forming machine, the combination with a vertically disposed mold, of a feeding - and - bending device for the 40 blank having a vertical spindle to permit of its oscillation, means to move said device toward and from the mold and to oscillate it, a pivoted lever engaging its spindle, and means to operate said lever to move said 45 spindle axially in an upward direction, thereby to raise the device, when said device has arrived at the end of its stroke, in a direction toward the mold, substantially as described.

50 12. In a counter-forming machine, the combination with a mold, of an oscillating feeding-and-bending device for the blank, including a head and having blank-engaging nippers, means to move said device to- 55 ward and from the mold and to oscillate it while it is being so moved, a cam, and means engaging said cam to move said nippers to bend the ends of the blank upward and inward, which means is associated with the 60 head and adapted to be operated by the oscillatory movement thereof, substantially as described.

13. In a counter-forming machine, the combination with a mold, of an oscillating feeding-and-bending device for the blank 65 including a head and having blank-engaging nippers, means to move said device toward and from the mold and to oscillate it while it is being so moved, means to raise said device when it has arrived at the end 70 of its stroke in a direction toward the mold, a cam, means engaging said cam to move said nippers to bend the ends of the blank upward and inward, and means which is associated with the head, and arranged to 75 be operated by an oscillatory movement thereof, said means permitting vertical movement of the head and parts supported by it, substantially as described.

14. In a counter-forming machine, the 80 combination with a mold, of an oscillating feeding-and-bending device for the blank including a head and having blank-engaging nippers, means to move said device toward and from the mold and to oscillate it 85 while it is being so moved, a cam secured to a support for the head, and means connected with said nippers and engaging said cam to operate said nippers to bend the ends of the blank upward and inward by and 90 during the oscillatory movement of the head, substantially as described.

15. In a counter-forming machine, the combination with a mold, of an oscillating feeding-and-bending device including a 95 head and having blank-engaging nippers and pinions connected therewith, and a rack-bar to move said pinions to move the nippers to bend the ends of the blank upward and inward, a cam, and means engaging said 100 cam and associated with the head and operated by the oscillatory movement thereof to move said rack-bar, substantially as described.

16. In a counter-forming machine, the 105 combination with a mold, of an oscillating feeding-and-bending device including a head and having blank-engaging nippers and pinions connected therewith, and a rack-bar to move said pinions to move the 110 nippers to bend the ends of the blank upward and inward, a cam secured to the support for the head, and means connected with said rack-bar and engaging said cam to move said rack-bar as the head is oscillated, 115 substantially as described.

In testimony whereof, I have signed my name to this specification, in the presence of two subscribing witnesses.

ALBERT F. JONES.
